RAZOR

James Robert Pamplin, Springfield, Mo.

Application April 21, 1932. Serial No. 606,718

4 Claims. (Cl. 30—12)

This invention relates to razors and particularly to a motor operated razor of simple construction and great utility.

It is an object of this invention to provide a 5 razor which will eliminate the necessity of using soap or other lathers and like materials in shaving.

A further object is to provide novel means for the cutting of hair from the surface of the 10 human body.

Another object is to provide a device of this character which is self sharpening, thus dispensing with the necessity of changing blades or removing blades for external sharpening as is 15 the case with the ordinary type of razor in use at the present time.

With these and other objects in view, the invention consists in certain novel features of construction, and combinations of parts as will 20 be more fully hereinafter described and claimed.

My invention is illustrated in the accompanying drawing, forming part of this application, in which

Figure 1 is an elevation of the completely 25 assembled device,

Figure 2 is a plan view of the same,

Figure 3 is a sectional view taken on line 3—3 of Figure 1,

Figure 4 and Figure 5 are enlarged fragmentary views of details of construction, hereinafter 30 to be more fully described,

Figure 6 is a sectional view taken on line 6—6 of Figure 3,

Figure 7 is a sectional view taken on line 7—7 35 of Figure 6, and

Figure 8 is an enlarged sectional view taken substantially along line 8—8 of Figure 1.

Referring to the drawing, I have shown therein a mechanically operated razor having the 40 usual flexible shaft and cable 10, a stationary handle 11, a base 12 attached thereto and having a U-shaped head 13 which forms a recess 14.

A revoluble shaft 15 connected to a suitable source of power is located within openings 45 16 and 17 in the head 13 and base 12 respectively.

Upon the end of the shaft is mounted an eccentric 18. Mounted upon this eccentric and located within the recess 14 is a movable blade 19 having angular cutting teeth 20 and having 50 slots 21 at opposite ends.

A U-shaped guide member 22 is slidably and revolvably mounted in a sleeve 23 at the rear of the head 13 and has its ends 24 mounted in the slots 21. An arcuate tensioning spring 25 is 55 located in the recess 14 and bears against the

head 13 and the blade 19, the shaft 15 passing through an opening 26 therein.

A stationary blade 27 having a sharpened edge 28 encloses the recess 14 and is held in place by suitable clips 29, the edge 28 coacting 60 with the teeth 20 of the movable blade.

In operation, the razor is used in the ordinary manner, the shaft 15 causing a rotary movement to be imparted to the blade 19, the teeth 20 of which take up the hair and force it against the 65 cutting edge 28 of the stationary blade 27, the guide member 22 coacting with the slots 21 to keep the blades parallel.

I have found that the use of my device dispenses with the need of any lather whatsoever 70 and have also noted that the spring 25 causes a grinding together of the blades 19 and 27, thus giving a self-sharpening razor.

Various slight changes might be made in the general form and arrangement of parts described without departing from the invention, and hence I do not limit myself to the precise details set forth, but consider myself at liberty 75 to make changes and alterations as fairly fall within the spirit and scope of the appended 80 claims.

I claim:

1. A razor having a straight edged stationary blade, an eccentrically operated superposed revoluble blade having inclined teeth coacting in 85 frictional contact with the stationary blade, means for extending the teeth over the edge of the stationary blade during a part of each revolution of the movable blade and for retracting them therefrom during the remainder of each 90 revolution, means for maintaining parallel relationship between the blades, resilient means for holding the blades in frictional contact and a frame for holding the various parts in cooperative relationship.

2. A razor having a straight edged stationary blade, a movable blade provided with inclined teeth in frictional contact with the stationary blade, an eccentric for imparting a rotary motion to the movable blade in the direction of 100 inclination of the teeth and for extending and retracting the teeth with respect to the stationary blade, means for maintaining parallel relationship between the blades, resilient means for holding the blades in frictional contact with 105 each other and a frame for holding the component parts in cooperative relation.

3. A razor having a stationary blade with a straight cutting edge, a movable blade having inclined teeth coacting in frictional contact with 110

the cutting edge of the stationary blade, means for maintaining parallel relationship between the blades, means for permitting the movable blade to be moved in any direction within its own plane and for preventing movement perpendicularly to its own plane, resilient means for holding the blades in frictional contact with each other, means for imparting rotary motion to the movable blade in the direction of inclination of the teeth and for extending and retracting the teeth with respect to the stationary blade and a frame for holding the component parts in co-operative relation.

4. A razor having a stationary straight edged blade and a movable blade having inclined teeth, the inner edges of the teeth forming cutting edges which coact in frictional contact with the edge of the stationary blade, means for causing the teeth to alternately project over and recede from the cutting edge of the stationary blade while in motion, resilient means for maintaining frictional contact between the blades and a frame for holding the component parts in co-operative relation.
